CLAIM

The ornamental design for a toy projectile launcher apparatus as shown and described.

DESCRIPTION

FIG. 1 is a front perspective view of a toy projectile launcher apparatus of the instant invention;

FIG. 2 is a left side elevational view thereof;

FIG. 3 is a right side elevational view thereof;

FIG. 4 is a rear elevational view thereof;

FIG. 5 is a front elevational view thereof;

FIG. 6 is a top plan view thereof; and,

FIG. 7 is a bottom plan view thereof.

The broken lines immediately adjacent to the shaded areas depict the bounds of the claimed design, while all other broken lines are directed to environment. The broken lines form no part of the claimed design.

1 Claim, 5 Drawing Sheets
